UNITED STATES PATENT OFFICE.

HUDSON W. HAKES, OF MILLBURY, MASSACHUSETTS.

SELF-THREADING LOOM-SHUTTLE.

1,168,628.

Specification of Letters Patent. Patented Jan. 18, 1916.

Application filed August 24, 1911. Serial No. 645,895.

To all whom it may concern:

Be it known that I, HUDSON W. HAKES, a citizen of the United States, residing at Millbury, in the county of Worcester and 5 Commonwealth of Massachusetts, have invented a new and useful Improvement in Self-Threading Loom-Shuttles, of which the following is a specification, accompanied by drawings forming a part of the same.

10 My invention relates to what are technically termed self threading shuttles for looms, in which the thread may be carried by hand from the bobbin in the bobbin chamber by a continuous passage to the eye 15 of the shuttle, with the opening of the eye provided at the delivery end with means for preventing the accidental escape of the thread from the eye, and with the shuttle also provided with a device for preventing 20 the ballooning of the thread.

The objects of my improvement are to provide the connecting passage between the bobbin chamber and the eye arranged to facilitate the threading and operation of the 25 shuttle; to simplify the construction of the shuttle and the eye to aid in their assembly; to provide a simple and easily attached device for the prevention of the ballooning of the thread, arranged to accomplish the easy 30 threading and operation of the shuttle; and to simplify the entire construction of the threading and delivery apparatus of the shuttle. I accomplish these objects by the mechanism illustrated in the accompanying 35 drawing, in which—

Figure 1 is a plan view of my improved shuttle; Fig. 2 is a view of one side of the delivery end of the same showing the delivery eye of the shuttle and Fig. 3 is a view 40 of the opposite side of the same end; Fig. 4 is a similar side view to Fig. 2 with a portion of the shuttle shown in central section; Fig. 5 is a transverse section of the shuttle on the line 5—5, Fig. 1; Fig. 6 is a detached 45 perspective view of the antiballooning device; Figs. 7—9 inclusive are detached perspective and side views of the delivery eye and Fig. 10 is a side view of a modification of the same.

50 Similar reference characters refer to similar parts in the different figures.

In the shuttle body 1 of the usual construction is the bobbin chamber 2 with a recess 3 at the delivery end. The recess 3 at its rear end opens directly into the bobbin 55 chamber 2 in alignment with the tip of the

bobbin 4. Transverse to the body of the shuttle and communicating with the forward end of the recess 3 is an approximately cylindrical opening 5 extending entirely across the shuttle, as shown by dotted lines in Fig. 1, and arranged to receive the cylindrical eye 7 which is provided with a radial lip 8 held in a radial slot 9 at the side of the opening 5 to prevent the rotation of the eye 60 65. The eye 7 is inserted in the transverse opening 5 at the end 10, shown in Fig. 3, extends entirely across the shuttle body and is arranged to deliver the thread on the opposite side at the end 11, as shown in Fig. 2. 70 Attention is called to the fact that the opening 5 is cylindrical entirely across the shuttle body, having no obstruction to interfere with its formation or the construction of the radial slot 9. 75

The eye 7 is made of sheet metal in cylindrical form and is provided with a transverse slot 12, which is arranged to coincide with the axis of the recess 3 when the eye is in position in the shuttle, as 80 shown in Fig. 5. From near the bottom of the slot 12 to the delivery end 11 of the eye is a longitudinal triangular space 12^a communicating with an oblique slot 13 which is arranged at the delivery end 11 to open 85 at the top of the eye 7, allowing the thread in the operation of threading to be drawn from the slot 12 upward into the eye 7, thereby facilitating the threading of the shuttle. One side of the sheet metal 90 composing the eye 7 is formed with the radial lip 8 toward the rear of the eye, arranged to enter the slot 9 and prevent the eye from turning. The passage of the thread into the transverse slot 12 is provided for by the 95 opening 14 in the radial lip 8, as shown in Fig. 9, in which the slot 12 is partially closed by the forward portion 15 of the lip 8. If desired, the forward portion 15 may be cut away to leave the slot 12 entirely 100 open, as shown in Fig. 10.

In the ordinary construction of a self threading shuttle, the accidental escape of the thread upward from the eye 7 after being threaded is prevented by an overhanging shoulder formed by the edge 16, Fig. 2, of the shuttle body, which is arranged to pass in front of the delivery opening slightly below the upper edge and thereby prevent the escape of the thread 110 from the eye by an upward movement. This shoulder of the upper edge 16 of the hori-

zontal slot 17 in the shuttle body in front of the eye 7 forms an obstruction to the boring of the opening 5 and also to the convenient excavation of the radial slot 9. 5 In the present shuttle the shoulder of the edge 16 in front of the eye 7 is not employed for this purpose, so that the formation of the transverse opening 5 and the slot 9 is facilitated, as already stated.

10 The upward movement of the thread from the eye 7 in my device is prevented as follows:—An arm 18 is extended outward from the sheet metal eye 7 at the delivery end 11 which supports a semicircular plate 19, Fig. 7, which, being held at a distance from the eye 7, allows the insertion of the thread from the oblique slot 13 over the upper curved portion 20 and beneath the lower edge 21 of the plate 19, by which the thread is prevented from upward escape as it is delivered from the eye.

15 The antiballooning device is shown in perspective in Fig. 6 and is arranged to be inserted in the recess 3 in front of the bobbin 4. The antiballooning device consists of parallel plates 22 and 23, separated by a less distance than the width of the recess 3 and provided at their upper ends with horizontal flanges 24, arranged to be 20 inserted in the shuttle body on opposite sides of the recess 3. The plate 22 is provided with a curved tongue 25 arranged to cross the distance between the plates 22 and 23 and enter a mortise 26 in the opposite plate 23. In the threaded shuttle the thread passes between the plates 22 and 23 beneath the tongue 25, by which the ballooning of the thread is prevented.

25 The upper edge 27 of the recess 3 is chamfered and the thread passes from the anti-ballooning device shown in Fig. 6 through the customary curved diagonal slot 28 and the horizontal slot 17 into the transverse slot 12 in the eye 7, from which it is delivered from the shuttle through the eye 7 beneath the lower edge 21 of the plate 19, by which its upward escape from the eye 7 is prevented. The outer end 29 of the tongue 25 is curved to cross the space 30 30 between the plates 22 and 23 and extend in the mortise 26. The tongue 25 is narrower than the width of the mortise 26 to provide for the easy insertion of the thread from above the plates 22 and 23 by means of the 35 mortise 26 around the tongue 25 into its final position below the tongue 25 from which it enters the slot 12 in the eye 7.

40 If desired, felt or other friction material may be inserted between the plates 22 and 23 below the thread to provide a frictional resistance for the same. The eye 7 is ordinarily made of slightly less diameter at its delivery end 11 to facilitate the movement of the thread from the slot 12 to the 45 interior of the eye 7 in threading the shut-

tle. By opening the oblique slot 13 at the top of the eye 7, the lower half of the eye is arranged to be solid and free from any openings or shoulders tending to engage the thread as it is delivered from the eye. The eye 7 is constructed of sheet metal rolled into cylindrical form in cross section, but having the delivery end slightly smaller than the opposite end, giving a slight taper to allow it to be driven into and fit tightly in the hole in the shuttle.

50 To thread the shuttle, the thread is taken from the bobbin 4 and drawn around the tongue 25 through the mortise 26 into the space 30 below the tongue 25. From the space 30 the thread is passed through the diagonal slot 28 and the horizontal slot 17 into the transverse slot 12 in the eye 7 in alignment with the space 30. From the slot 12 the thread is passed through the oblique slot 13 into the interior of the eye 7, then around the plate 19 and below the lower edge 21 where it is in position to be delivered from the bobbin.

55 I claim,—

1. In a hand threading shuttle, a cylindrical delivery eye with a transverse slot in its upper side and an oblique slot extending from the forward lower portion of the transverse slot to the top of the delivery end of the eye, the inner end of the upper edge of the oblique slot being turned outwardly to form an eye retaining lip and to provide a triangular opening through the wall of the eye at the junction of the inner end of the oblique slot and the forward end of the transverse slot.

60 2. In a hand threading shuttle, a cylindrical delivery eye with a transverse slot in its upper side and an oblique slot extending from the forward lower portion of the transverse slot to the top of the delivery end of the eye, the inner end of the upper edge of the oblique slot being turned outwardly to form an eye retaining lip and to provide a triangular opening through the wall of the eye at the junction of the inner end of the oblique slot and the forward end of the transverse slot, one end of said retaining lip projecting over the transverse slot to assist in retaining the thread.

65 3. In a hand threading shuttle, a shuttle body, a delivery eye transverse to said shuttle body and having an opening at its top to receive the thread, and a plate spaced from the delivery end of said eye and integral therewith, with the lower side of said plate below the plane of the top of said eye, whereby the direct upward movement of the thread from said eye is prevented and with the upper edge of said plate curved to correspond with the curvature of the inner wall of the eye.

70 4. In a hand threading shuttle, a shuttle body with a transverse cylindrical opening,

a cylindrical delivery eye inserted in said opening, a plate held in front of the delivery end of said eye, the outer surface of said plate being smaller than the adjacent end of said eye, the lower edge of said plate being arranged to prevent the direct upward movement of the thread when in position in said eye, and the upper edge of said plate being curved concentrically with

10 the adjacent end of the eye.

5. In a hand threading shuttle, a shuttle body, a delivery eye transverse to said shut-

tle body, an arm extending outwardly from the delivery end of said eye, a semicircular plate carried by said arm in front of 15 said eye, with the outer curved edge of said plate concentric with and having a smaller radius than the delivery end of said eye, and with the straight edge of said plate extending across the delivery end of said eye. 20
